LUIS DRESCHER, OF NEW YORK N. Y.

Letters Patent No. 99,414, dated February 1, 1870.

IMPROVEMENT IN ELECTRO-MAGNETIC MACHINES FOR MEDICAL PURPOSES.

The Schedule referred to in these Letters Patent and making part of the same.

I, LUIS DRESCHER, of the city, county, and State of New York, have invented certain new and useful Improvements in Electro-Magnetic Machines for medical and other purposes, of which the following is a specification.

The first part of my invention relates to the suspension of the plates of a galvanic battery, by means of a hinge-jointed rod, sliding vertically through a suitable collar in the covering-plate or cross-bar of the battery, and provided with a scale thereon graduated to indicate the extent of the immersion of the plates when let down into the battery solution, the object of this part of my invention being to prevent, with certainty, an accidental immersion of the plates when the battery is not in use, and to ascertain also by a simple inspection of the rod the amount of battery-power obtained when the battery is in use, as determined by the depth to which the plates are immersed.

The second part of my invention relates to the combination of a movable platina plate with that part of the vibrating armature-lever or spring of an electro-magnet, which plays against the adjusting-screw connecting it with the battery, the object of this part of my invention being to provide, by a movement of the plate, for the ready preservation of a fresh metallic surface at the point of contact, as soon as said point shall have become oxidized in use.

The third part of my invention relates to the interposition of a reotrope or commutator, between the electro-magnetic machine and the electrodes, to be applied to the person of a patient, whereby I am enabled to change and reverse instantly the course of the primary and secondary currents from the machine without altering the conducting-wires, the reotrope being arranged for the purpose upon the base-plate of the machine.

The fourth part of my invention relates to the combination of a reotrope or switch-levers directly with one of the electrodes of the apparatus, which I denominate a "universal electrode," so as to be operated by the operator's finger whilst he is using the instrument, the object of this part of my invention being to enable the person using the apparatus either to interrupt or to reverse at will and with rapidity, if desired, the currents from the machine, and obtain an alternate inversion of the polarity of the electrodes by a simple pressure upon a knob on the handle of the improved electrode, even whilst both hands are engaged.

Figure 1, in the accompanying drawings, is a view in perspective of my improved galvanic battery and electro-magnetic machine, and of the improved reotrope and electrode connected therewith, illustrating the arrangement and mode of connections of my apparatus complete.

Figure 2 is a side elevation of my electro-magnet, with its base-plate in section.

Figure 7 is a transverse section of my "universal electrode," in the line drawn at *z z* in fig. 1.

Figure 3 is a longitudinal central section thereof in the line *y y* of fig. 7.

Figures 4 to 6, inclusive, are longitudinal sections in the line drawn at *z z* of fig. 7, illustrating each a different position of the switch-levers or current-changers therein.

Figures 8 and 9 are horizontal sections of a reotrope or current-changer on the base-plate of the electro-magnet of the apparatus, taken in a line drawn at *w w*, fig. 1.

A represents an ordinary galvanic battery.

B, a jointed hinged rod, to the lower end of which I fasten, by means of a screw or otherwise, the positive plate *C* alone, or both the positive and negative plates *C' C'*.

This rod *A* slides freely through a collar in the cap-plate *D*, covering the battery, and by its means the plates connected therewith may be lifted up out of the solutions of the battery.

The hinged joint *b* of the rod is so arranged, as illustrated in the drawings, that when the plates are lifted out of the solutions in the battery, the upper joint may be folded over at about a right angle, (see fig. 1,) to secure it and prevent it from dropping back, as is frequently the case where an unhinged rod is used. The joint in the rod overcomes also the inconvenience attendant upon the upright projection of a rigid rod, which necessitates the use of a much larger case or box to enclose it, and makes the battery top-heavy.

A properly-graduated scale is placed or marked upon the rod *A*, to indicate accurately the depth of immersion of the battery-plates, according to well-known natural laws. The relative strength and quantity of the galvanic battery may be determined by the simple inspection of the scale.

E is an electro-magnet, arranged upon a suitable base-plate, *I*, and

F is a vibrating armature-spring or lever, carrying a suitable armature, *F'*.

To the outer face of this vibrating spring or lever *F*, and near its lower extremity, I pivot a circular platina plate, *f*, fig. 2, so that it may be revolved upon said pivot as its axis.

G is an adjustable connecting-screw, working through a plate, *g*, secured to the edge of the bed-plate or base *I* of the magnet, and whose point strikes against the circular plate *f*, at or near the outer edge thereof. By this arrangement, when the electric sparks shall have oxidized the point of contact between the end of the screw *G* and the circular platina plate *f*, so as to cause

the vibrations, and also the shocks, to become irregular, a slight turn of the platina plate f will cause a new point of contact to be presented to the screw G , and the vibrations and shocks will again become regular.

H is an adjustable elastic fork, pivoted at one end (so as to play in a vertical plane) by means of a pivot-screw, h , to a pillar or support, K , secured upon the base-plate I of the magnet, on one side of its armature-lever or spring F , as illustrated in fig. 1. The free end of the fork embraces the lever F between its prongs, as shown in the drawings, so as to limit the extent of its vibrations.

Y is a stiff metal bar, pivoted at one end to the screw k of the fork H , to the pillar K , on the side thereof, opposite to the fork H , so as to project parallel therewith, and move in common with it on their pivot k as a centre.

At the extremity of this stiff bar Y , a set-screw, M , is placed to work against the elastic fork, and regulate its position laterally, with reference to the vibrating armature-spring or lever F .

When the fork is depressed, so that its prongs embrace the lower end of the armature-lever F , near the platina plate f , the upper end of the lever can vibrate freely, but when the fork is raised, its prongs will, in proportion to the extent of its elevation, limit the space for the vibrations, and consequently increase their rapidity. The extent of the vibrations will, therefore, be most limited, and the rapidity the greatest, when the prongs are directly underneath the armature F , and be greatest in extent and less rapid when they are dropped to the base-plate I . This control of the vibrations of the lever F is of great importance in the therapeutics and the diagnosis of diseases.

J is a reotrope or current-changer, made of a simple plate of any non-conducting material, pivoted upon the base-plate I of the electro-magnet by means of a central-pivot-screw, j . It is provided with an index-point at one end, as illustrated in the drawings, figs. 1, 8, and 9. Its movement upon its pivot j is limited by means of two stops or pins i j , upon the base-plate I , as shown in figs. 8 and 9.

L L' are two binding-posts, secured upon the reotrope-plate J , in a right line drawn longitudinally and centrally upon the plate at each end thereof, at points equally distant from its centre. These posts hold the wires extending to the electrodes of the apparatus. Their lower ends extend through the plate J , so as to project very slightly from its under surface, forming points to come into contact when necessary with current-connecting points or pins in the base-plate beneath.

Two additional projecting metallic points, united by an insulated wire, m , are secured upon the under surface of the reotrope-plate J , the one being placed upon one side of the end of the post L , and the other at a corresponding distance from the end of the other post L' , but on the opposite side thereof, as illustrated by the double dotted lines in figs. 8 and 9.

n n' and p p' are four insulated metallic pins or points inserted into and through the base-plate I , immediately under the reotrope-plate J , and upon each side of the ends of its binding-posts L L' . These points are so fixed as that when the reotrope-plate J is parallel to the edge of the base-plate I , two of them, n p , are at equal distances from the end of the binding-post L , at one end thereof, and the other two, n' p' , at like equal distances from the binding-post L' , at the other end, as illustrated in fig. 8 of the drawings. The two points n n' are connected respectively with the armature-spring F and adjusting screw G , and the other two, p p' , with the outer and inner coils of the magnet.

The correlation of all these connecting-points is

such, that when the reotrope lies parallel with the edge of the base I , as illustrated in fig. 8, the lower end of the binding-posts L L' projecting through it, will be free from contact with any points, so that the wires leading thence to the electrodes will be cut off from any connection with the magnet-instrument E E' . At the same time, the two points connected by the wire m , will rest free from contact with other points, and the instrument will be at rest.

By turning the reotrope J to the left, so that its index shall point to the numeral I^o , marked upon the base I , as shown in fig. 9, the projecting end of the binding-posts L L' will be brought into contact, the one, L , connected with one of the electrodes, with the point p , connected with the adjusting and connecting-screw G of the instrument; the other, L' , connected with the second electrode, with the point n' , connected to the armature-lever or spring F , so that the circuit of the primary currents obtained from the battery A and primary coil E , may be closed through these electrodes O X , whilst the connected points m will be brought into contact respectively with the magnet-points n p , thus closing the circuit for the secondary currents passing through the sliding coil E' of the magnet.

By turning the reotrope-plate J in the contrary direction, so that its index shall point to the numeral II° , upon the base-plate I , the ends of the binding-posts L L' , holding the electrode-wires, are brought into contact, respectively, with the magnet-points n p , thus establishing a direct circuit for the secondary currents through the electrodes, whilst the contact of all other connecting-points is broken.

It will now be understood how, by moving the index of the reotrope J to I^o or II° , figs. 1, 8, and 9, the primary currents can be instantaneously changed with the secondary currents, or vice versa, without altering the conducting-wires.

From the fact that the intensity of the primary currents is diminished when the wire coil E' , with closed circuit, is moved over the primary coil of the electro-magnet E , we are enabled to regulate directly the primary currents, by moving the coil E' inward or outward, (see dotted lines, fig. 1,) when the circuit is closed by the wire m and its connecting-points, as illustrated in fig. 9, and hence greater convenience and precision in the application of the electric currents is obtained with this apparatus, than can be reached by any other now in use.

O is an improved electrode, which I denominate the "universal electrode." It is constructed as follows:

A plate, Q , of wood, or other insulating-material, is formed and arranged to pass into an outer shell or case, O , which shell or case constitutes a handle for the instrument.

Upon this plate Q , two metallic strips, P P' , figs. 4, 5, and 6, are secured by screws, so as to lie parallel to each other without contact. Their outer ends project beyond the plate and its case.

Upon their inner ends are pivoted the inner ends of two metallic switch-bars, R R' , in such a manner as that the outer-ends of said bars shall be free to vibrate upon said pivots in a plane parallel with the face of the board Q .

These pivoted switch-bars R R' , are coupled, near their outer-ends, by a pivoted link, S , made of an insulating substance, and a spring, r , is secured upon one edge of the plate Q , as illustrated in fig. 4, to bear against the bar R , and force the two laterally against the opposite side of the case enclosing them.

A small knob, U , is secured to the bar R' , so as to project therefrom outside of the casing O , and a sliding catch, s , is placed on the exterior of said casing, to engage a projection or offset, u , upon the knob, and confine the same when it has been pushed partly in.

ward, overcoming the pressure of the spring r , and bearing down the pivoted bars $R R'$ to a right position, as illustrated in fig. 6.

At the end of the plate Q , immediately under the free ends of the pivoted bars $R R'$, three insulated metallic pins, $t t' t''$, are inserted at equal distances apart. (See fig. 7.)

The two outer pins $t t''$, are connected by suitable wires on the under side of the plate Q , with a rod, T , projecting from the front end of the electrode, (see figs. 4, 5, and 6,) and the central pin t' is connected to a rod, W , extending back under the plate Q to the rear end of the electrode, (see fig. 3,) from which it projects, to receive a wire, connecting it with a second ordinary electrode X , fig. 1.

The outer ends of the strips $P P'$ project also rearwardly from the end of the electrode O , and are connected by wires with the binding-posts $L L'$, on the reotrope J of the apparatus.

By the action of the operator's finger on the knob U of the "universal electrode," the switch-bars $R R'$ can be moved into three different positions, viz:

First, so that their free ends shall touch and come into metallic contact with the two pins $t t'$, respectively, as illustrated in fig. 4. The bars are thrown into this position by the action thereon of the spring r , when released by the disengagement of the catch s from the knob U . When the bars are thus placed, the electric current entering along the metallic strips P from the electro-magnet instrument, follows the metallic conductor through the bar R' to the point t , and thence to the rod T , whence, if the two electrodes, O and X , be both applied to the human body, it will pass through to the second electrode X , and re-entering the "universal electrode" at the end of the rod W , by means of the wire extending thereto, will pass through the same by the point t' , the bar R and strip P , and continue back by its connecting-wire, to the electro-magnet, thus completing its circuit. We have therefore, in this first position of the switch-bars $R R'$, fig. 4, the positive pole (+) of the apparatus, at the rod T of the "universal electrode," and its negative pole (−) at the end of the second electrode X .

In the second position of the switch-bars, they are forced by the pressure of the operator's finger on the knob U , across the plate until their ends rest respectively on the points $t' t''$, as illustrated in fig. 5. When they are in this position, the direction of the currents through the electrode is reversed. The current entering as before, through the strip P' and bar R' , is conducted to the rod W , and led to the electrode X , from whence it passes through the body in a reverse direction to the rod T of the "universal electrode," and thence back through the bar and strips $R P$ to the connecting-wire, returning it to the instrument. In this case, then, we have T as the negative (−) pole and X as the positive (+) pole of the apparatus.

The third position of the switch-bars is that illustrated by fig. 6 of the drawings, in which their ends,

being insulated, by resting upon the blank spaces between the connecting-points t and $t' t''$, break all contact with the connections therefrom to the poles of the electrodes, and hence discontinue or break the circuit through them. In this position the bars may be secured by means of the sliding catch s , as hereinbefore described.

The conducting wires or cords extending from the reotrope to the electrodes are insulated, and then passed jointly through a single India rubber tube, to protect them from injury.

I prefer to make the enclosing shell or case of the electrode O cylindrical, as illustrated in fig. 1, to serve as a handle to the operator, although it may be of any other convenient form or shape.

The functions of the "universal electrode" O will now be obvious, namely: Simple interruption of the current, (see fig. 6,) alternate interruption and connection, (see figs. 6 and 4 or 6 and 5,) and alternate inversion of the polarity of the electrodes, (see figs. 4 and 5,) and the fact that these alternate interruptions and inversions can be performed by the operator at will, with variable rapidity and exact precision, even when both hands are engaged, through a simple pressure of his finger upon the knob of the instrument while operating, determines at once the great value and advantage of my improvement in its application to electro-therapeutics.

I claim, as my invention—

1. The hinge-jointed rod B , provided with a graduated scale thereon, and combined with the plate C or plates $C' C'$ of a galvanic battery, and with a supporting-bar or plate D above the same, substantially in the manner and for the purposes herein set forth.

2. The combination of a movable platina plate on the armature-spring or lever of an electro-magnetic machine, with the adjusting and connecting-screw of the battery circuit operating therewith, all substantially in the manner herein set forth.

3. The combination of a movable, adjustable insulated fork H , with the armature-spring or lever of an electro-magnetic machine, substantially as and for the purpose herein set forth.

4. The combination of a reotrope, J , with the circuit wires and electrodes of an electro-magnetic machine, when said reotrope is arranged and made to operate substantially as herein described.

5. The combination, with an electrode T , of metallic conducting-strips $P P'$, switch-bars $R R'$, insulated points $t t' t''$, and rod W , all arranged, connected, and made to operate substantially as and for the purpose herein set forth.

The foregoing specification of my improvements in electro-magnetic machines, signed by me, this 20th day of November, A. D. 1869.

LUIS DRESCHER.
